Primary Examiner — Bridget L Eland*Assistant Examiner* — Lauren McVey(74) *Attorney, Agent, or Firm* — Lathrop Gage L.L.P.(57) **CLAIM**

The ornamental design for a nasal dilator, as shown and described.

DESCRIPTION

FIG. 1 is a perspective view of a nasal dilator, showing my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof;

FIG. 7 is a front elevation view thereof; and,

FIG. 8 is another perspective view of the nasal dilator of FIG. 1, shown with environment.

The broken lines are directed to environment; the broken lines form no part of the claimed design.
